(57) **CLAIM**

We claim the ornamental design for a door for washing machine, as shown and described.

DESCRIPTION

FIG. 1 is a front perspective view of a door for washing machine showing our new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof;
 FIG. 7 is a bottom view thereof;
 FIG. 8 is a rear perspective view thereof; and,
 FIG. 9 is a front perspective view of the door for washing machine in which a washing machine in broken lines is provided to illustrate an example environment.
 The short dash-dot broken lines showing of unclaimed portions of the door for washing machine in the figures form no part of the claimed design. The short dash-dot lines showing of the washing machine in FIG. 9 are for illustrating environmental structure and form no part of the claimed design.
